UNITED STATES PATENT OFFICE

WALLACE C. BENNETT, OF HINGHAM, MASSACHUSETTS

LININGS FOR SHOES AND THE LIKE

No Drawing.

Application filed April 24, 1928. Serial No. 272,568.

This invention relates to linings for shoes and the like. The invention has been applied more particularly to the converting of grey goods for shoe linings, and will be here-
5 in described in this phase of its utility.

For shoe linings the grey goods are usually either bleached or dyed, but in many cases are merely finished in the grey by being stiffened so as to stand up well in the
10 shoe. The invention introduces a feature which has the double effect that it makes the product permanently promotive of foot-
health, foot-sanitation and foot-comfort, or
at least very durably so, and that it makes a
15 lining whose initial purity is but little affected by wear, with incidental perspiring of the
wearer's foot. Also the lining has longer life
than ordinary lining, without being appreci-
ably more expensive. By reason of the in-
20vention, peculiar astringent, aseptic and
odor-preventing qualities become associated
with the lining or inter-lining of a shoe.

To these ends a proportion of a suitable
25 ingredient is to be incorporated in the siz-
ing material, by mixture before the siz-
ing is applied. Zinc stearate may be con-
sidered as one example of such an ingredient,
producing the result that when the goods,
30 sheet duck for example, are sized in the
course of their normal converting for shoe
linings, the duck becomes a carrier of proper-
ties which, when it is later incorporated in
a shoe, tend to allay the irritating and odorous
35 effect of perspiration and to keep the
whole shoe sweet and wholesome. This in-
gredient also imparts to the lining a char-
acter eliminating chafing, thus reducing
wear upon hosiery and upon feet; and the
40 lining becomes soothing to the feet, with
astringent effect upon the skin and pores.

These highly desirable qualities are im-
parted to a shoe approximately without ex-
tra cost. The added ingredient acts to a
45 certain degree as a filler; in consequence of
which less of the usual filler, such as starch,
will be required. And because stearates as a
rule are bulky, the added ingredient may
occupy considerable space relative to its pro-
50 portion of weight. But these effects are rel-
atively minor and incidental, for it is a pe-

culiar fact that an extraordinarily small
quailty of the zinc stearate suffices. For
example, for treating a duck sheet weighing
ten ounces to the yard, a suitable bath may
have the regular sizing and the zinc stear-
ate ingredients mixed in a 200 to 1 ratio.
55 Notwithstanding this small proportion it is
observed that the stearate, by its smooth,
waxy feel, tends to smooth the surface fibres
in the cloth, diminishing the chafing, and
reducing the wear on lining and hosiery.
60 Therefore it is considered that perhaps the
stearate forms as a coating over particles of
the size. But regardless of the correctness
of this suggestion as to the structural ar-
rangement of the stearate in reference to the
65 main body of sizing, there is an important
effect in that in some manner it produces in
the sizing an environment in which life and
growth of microscopic plant or animal forms
70 are inhibited. As a probable explanation,
it is surmised that the odor which ordinarily
develops in shoes, and which the invention
avoids, is due to a bacterial growth in per-
spiratory matter excreted from the wearer's
75 foot, akin to the bacterial growth called
putrefaction which is familiar in vegetable
and animal foods. The sizing material em-
ployed for shoe lining often consists largely
80 of starch. Starch is a favorable medium for
growth and multiplication of bacteria, espe-
cially in presence of moisture. The ingredi-
ent introduced by the invention creates an
environment which is unfavorable to the
85 growth of bacteria, and which is in that
sense germicidal because it inhibits germ
life, operating much as a so-called "preserva-
tive" prevents fermentation or putrefaction
when added to a food substance. Thus the
90 notable results attained in this respect in
shoes are due to the change of environment
for germ life produced by the invention.

Taking zinc stearate as an example, the
zinc atom when in combination is known to
be astringent and germicidal; and the stear-
ic acid radical gives to the stearate mate-
rial a quality such that although it is a fat-
ty residue nevertheless certain kinds of de-
terioration do not easily occur. This is true
95 of the cognate fatty acids, all vegetable fats
100

being characteristically permanent. For the purposes of the invention one may use a derivative of a fatty acid not differing materially in molecular weight from the stearic, 5 palmitic and oleic acids (the stearates being preferred to the oleates and palmitates because of not liquefying at so low a temperature) in which is combined a metal whose salts are known to have astringent or anti-septic properties, or both; but ordinarily avoiding those whose salts are poisonous to human beings, and those whose salts are soluble in water and therefore might wash out when wet by water or perspiration. Zinc 10 and aluminum are metals which meet these specifications. They are amphoteric, in that each may act both as an acid-forming and a base-forming element, and each has salts which are non-poisonous and are insoluble 15 in water.

The protective material, selected on the above principles, or otherwise found suitable, is added to the sheets of grey goods, along with their sizing; and it takes final 20 form as an impregnating solid substance which imparts the desired germicidal, astringent and anti-friction properties. Its introduction may be accomplished by the apparatus and methods by which sizing 25 alone has hitherto been applied. Preferably the substance is preliminarily thoroughly mixed with the size in liquid form; and the woven sheet material is run through a bath of this mixture in a trough, according 30 to usual practices of sizing. As the sheet takes up the mixture, both ingredients thereof become impregnated into the grey goods so as thoroughly to disseminate each throughout the sheet. The relative proportions 35 of the ingredients in a particular bath may vary somewhat according to the weight per yard of the sheet material to be treated. A lighter sheet may require in its bath proportionately slightly more of the deodorant 40 and antiseptic substance.

In the zinc or aluminum stearate, or oleate, the metal furnishes astringent properties which tend to close the pores of the feet, thus retarding perspiration; and the 45 fatty acid makes the stearate or oleate be demulcent, soft and waxy feeling, and non-abrasive and giving the cloth a soothing and soft-feeling quality; and both metal and fatty acid contribute to the environment 50 which discourages bacterial growth. The same effect can be obtained, to a degree, by a combination of talc and sodium borate which would have the anti-friction, anti-septic and astringent qualities.

55 The result is a prolongation of the useful life of shoes and of hosiery; a more wholesome condition for both; and for the wearer a greater degree of foot comfort and foot health.

60 Although especially developed with re-

gard to shoe linings, the invention is not limited to that use. The invention may, for example, be found useful for sweat bands in hats; or as a fabric, lining, or casing for dress shields. In the case of sweat bands a 70 fabric like that above proposed for shoe linings but well filled with a larger proportion of the material would be suitable for inexpensive hats.

And although by the preferred method 75 herein described it is applied by admixture with the sizing, it would appear that a protective material could be applied to the sheet duck otherwise, as by treatment after or before the application of the sizing.

What is claimed is:

1. As a new article of manufacture, a lining for shoes and the like comprising a sheet of textile fabric impregnated with starch, throughout which is disseminated a solid, 85 astringent salt of stearic acid.

2. As a new article of manufacture, an astringent lining for shoes and the like comprising a sheet of starch-impregnated textile fabric throughout which is disseminated 90 a small proportion of zinc stearate.

Signed at Boston, Massachusetts, this twenty-third day of April 1928.
